UNITED STATES PATENT OFFICE.

PHILIP A. MYERS, OF ASHLAND, OHIO.

DESIGN FOR A HOME TRAINER ATTACHMENT.

SPECIFICATION forming part of Design No. 29,347, dated September 13, 1898.

Application filed May 3, 1897. Serial No. 634,950. Term of patent 14 years.

To all whom it may concern:

Be it known that I, PHILIP A. MYERS, a citizen of the United States, residing at Ashland, in the county of Ashland and State of Ohio, have invented and produced a new and original Design for a Home Trainer Attachment, of which the following is a specification, reference being had to the accompanying drawings, in which—

10 Figure 1 is a side elevation of the attachment, and Fig. 2 a front view.

The leading feature of my design consists in a U-shaped frame having a roller between the open ends of the U and with projections 15 extending from the cross-bar at the closed

end of the U. As shown, the attachment is composed of two parallel bars *a a*, connected by a cross-bar *b*. At the open end of the U-frame is a roller *c*, connecting these ends. From the cross-bar *b* projections *d* extend. 20

I claim—

The design for a home trainer attachment herein shown and described.

In testimony whereof I affix my signature in presence of two witnesses.

PHILIP A. MYERS.
